UNITED STATES PATENT OFFICE.

GEORGE P. BRAND, OF NEW YORK, N. Y.

MECHANICAL SHEET-CONTROLLING MEANS.

1,269,045.

Specification of Letters Patent. Patented June 11, 1918.

Application filed April 13, 1915. Serial No. 21,165.

To all whom it may concern:

Be it known that I, GEORGE P. BRAND, a citizen of the United States, residing at New York, in the county of New York and State of New York, have invented certain new and useful Improvements in Mechanical Sheet-Controlling Means, of which the following is a specification.

This invention relates to certain new and useful improvements in mechanical means for controlling a traveling sheet or web, such, for instance, as is employed in automatic musical instruments. It has for its objects among others to provide a simple and efficient web or sheet controlling means, purely mechanical, without the employment of pneumatics or analogous devices and which shall be reliable in its action and not affected, as are pneumatic devices of this nature, by leakage of air or by stoppage of openings by lint or other extraneous matter. My present construction, furthermore, is easily adjusted, practically frictionless, being most sensitive in its movement, requiring but little pressure of the paper upon the edge guides to cause movement of the transmission mechanism.

I provide mechanically for the use of sheets of different widths without affecting the operation of the other mechanism by the introduction of the sheet of whatever width.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which Figure 1 is a front elevation with portions broken away, showing the application of my present improvement.

Fig. 2 is a top plan.

Fig. 3 is a perspective view with portions broken away, showing my present improvement removed from the instrument.

Fig. 4 is an enlarged end elevation with portions in section, looking in the direction of the arrow in Fig. 3 as on the line 4—4 of Fig. 1 looking in the direction of the arrows.

Fig. 5 is a substantially central vertical section from front to rear as on the line 5—5 of Fig. 1, looking in the direction of the arrows and on an enlarged scale.

Fig. 6 is an enlarged sectional view, as on the line 6—6 of Fig. 2.

Fig. 7 is an enlarged detail partially in section and partially in elevation, showing the connection of one of the carriage hangers.

Like numerals of reference indicate like parts throughout the different views.

My present improvement resides broadly in a mechanical sheet controlling device 65 operable without the employment of pneumatics and I wish it so considered. The other elements of a mechanical musical instrument herein shown and hereinafter referred to are herein disclosed merely for the purpose of illustration and showing the application of my present improvements, it being understood that the invention thus broadly stated is in no wise restricted to any particular construction of the elements 70 of the instrument other than as hereinafter specified.

The music box 1, the take-up spool 2, trackerbar 3, the music spool 4, its spindles 5 and the rewind mechanism 6, as well as the sprocket chain 7 and sprocket wheel 8, are of any well known or approved form, the latter being mounted upon the shaft 9, which, as will be hereinafter described, constitutes a part of the transmission device 85 which comprises the two U-shaped members 10 and 11 fixedly secured together and having the depending portions 12 and 13 respectively at their opposite ends and in which depending portions at one end the shaft 9 is mounted, as seen in Fig. 1. A suitable brace, as shown at 14, may be employed, if necessary, to hold the depending portions 12 and 13 in their spaced relation. The members 10 and 11 may be made of 90 aluminum or other suitable material combining strength and lightness and they are supported upon the uprights 15 which at their upper ends carry the pins or the like 16 which are mounted loosely in the adjacent portions of the innermost U-shaped bar, as seen clearly in Fig. 1. The lower ends of these uprights 15 are mounted upon screws or the like 17 held in the ends of the music box, washers or the like 18 being provided between the said uprights and ends, as seen in Fig. 1. These uprights are free to oscillate within certain limits in the direction of the length of the music box.

Extending from one end of the music spool 110

box is a bar or arm 19 affixed thereto in any suitable manner and in this bar is pivotally mounted, as at 20, the oscillating member 21, the upper end of which is in this instance shown as bifurcated, as shown at 22, which bifurcation loosely receives a pin 23 extending laterally from the horizontal portion of the U-shaped member 10, as shown clearly in Figs. 1 and 3. The lower end of this oscillating member 21 is in the form of a segment, on the arc of a circle of which the pivot 20 is the center. The lower face of this segment is toothed, as seen at 25, and meshes with a toothed wheel 26 carried by a shaft 27 mounted at one end in the arm 28 secured to the end of the music box and its other end carries a friction wheel 29, the periphery of which is preferably milled or roughened, as seen at 30 as seen in Fig. 2, or it may be smooth, as seen in Fig. 3. This end of the shaft is journaled in an arm 31 which is fixedly secured, as at 32, to one end of a swinging suspended carriage 33, as seen best in Fig. 3, in which latter view the parts constituting my present invention are shown in perspective separated from the machine proper but with the parts in their relative positions. This carriage is suspended by the bails or hangers 34, one at each end, the cross portions 35 of the bails being mounted for free movement in the members 36 which are attached to the inner faces of the ends of the music spool box, as seen in Fig. 1, and their lower ends are preferably connected with the carriage 33, as seen in Fig. 7 wherein the members 34 are shown as screw threaded at 37 and pass through openings in the carriage 33, being provided upon their lower ends with nuts 38 or the like 39, preferably seated in sockets 39 in the under face of the carriage and buttons or the like 40 provided upon the upper face of the carriage and seated thereupon. This provides for the necessary adjustment, as well as ready assemblage of the parts or removal thereof for repairs or other purposes when desired.

Pivottally mounted on the upper face of the carriage 33, as at 41, are the preferably flat bars 42 which, in the present instance, are shown as twisted near their outer ends, as at 43, to form the substantially vertical members 44 which serve as edge guides to contact with the opposite edges of the note sheet 45. The terminals of these edge guides are outwardly inclined or rounded, as seen at 46 in Figs. 2 and 3, so as to offer no resistance to the insertion of the music sheet so as to avoid any tendency to injure the latter. Springs 47, as seen in Figs. 2 and 3, are provided, bearing against these bars 42 near their pivots, tending to normally hold the bars inward toward each other and substantially parallel with each other. They are sufficiently delicate to per-

mit of ready outward movement of the bars 42 by the pressure of the edges of the music sheet thereagainst. The bars 42 are connected to move in unison by plates 48 secured at their outer ends to the bars 42 in any suitable manner and at their inner ends connected together, in the present instance by means of a pin or the like 49 on the one member engaging in an elongated slot 50 in the other member, as seen in Figs. 2 and 3, so as to permit of the necessary endwise movement of the two members 48 within restricted limits. During the operation of playing the edge guides are designed to control and compensate for the lateral deviations of the note sheet, but upon the rewind these edge guides are pulled outward away from each other and out of contact with the note sheet. In the present instance I have shown one convenient way in which this may be accomplished and attention is called to Figs. 1, 2 and 3 in which 51 is a member operable outward from the adjacent end of the music box when the mechanism is thrown into position for rewind, and this member carries an arm or rod 52 suitably mounted and guided and connected with the adjacent arm 42 in any suitable manner, such, for instance, as seen in Fig. 3, so that when said member 51 is moved outward in placing the mechanism in condition for rewind, the said arm 42 is pulled outward and, consequently, the other arm is moved in the opposite direction so that all liability of injury to the edges of the sheet as the latter is rewound upon the music spool is obviated.

The friction wheel 29 is disposed between two disks 53 and 54, the adjacent faces of which are preferably faced with rubber or analogous material, as seen best in Fig. 6. These disks 53 and 54 are carried by the sleeve 56 loosely mounted on the shaft 57 supported at one end in the adjacent end of the box 1 and at the other end in an upright 58 extending from an arm 59 secured to the adjacent end of the box 1, as seen in Fig. 1. The diameter of the friction roller 29 is but slightly less than the space between the adjacent faces of the two disks 53 and 54, as seen in Fig. 1, so that while there is room for some play of this roller between the disks, this play is very slight, in practice possibly not more than two one-thousandths of an inch.

The sleeve 56 carries a sprocket wheel 60, as seen best in Fig. 6. The disks and the sprocket wheel 60 are held against movement longitudinally of the shaft 57 by any suitable means, such as collars 61 and 62 secured to the shaft by screws or the like 63, as is also clearly seen in Fig. 6.

Motion is imparted to the sprocket wheel 60 and, consequently, to the disks 53 and 54 by means of a sprocket chain 64 passed around said sprocket wheel 60 and around

a sprocket wheel 65 on the shaft 66 of the take-up spool.

The wheel 65 is held against movement lengthwise of the shaft 66 by suitable means, as a collar 67, secured to said shaft, as seen in Fig. 1. 68 is the hub of the sprocket wheel 65, its periphery being toothed to constitute a ratchet, as seen clearly in Figs. 1 and 4. This is loosely mounted upon the shaft 66 and is caused to turn therewith in one direction by means of a dog or pawl 69 pivotally mounted on the face of the hub and engaging a toothed collar 70 fixedly secured to the shaft in any suitable manner. 71 is a dog or pawl pivotally mounted, as at 72, upon the under side of the member 59, see Figs. 1 and 4, and adapted to engage the teeth of the ratchet wheel 68 to prevent retrograde movement thereof, but permitting of its turning freely in the other direction.

During the operation of playing, the sprocket wheel 65 revolves with the shaft 66 and through the medium of the sprocket chain 64 and sprocket wheel 65, the disks 53 and 54 are continuously revolving. On the rewind, however, it is desirable to have the guides moved outward away from the edges of the note sheet and to throw the friction wheel 29 out of operation so as to hold the music spool from endwise movement. Consequently, when the member 6 is moved to the right for rewind, the edge guides are moved simultaneously outward through the connections 51 and 52 hereinbefore described and the ratchet wheel 68 is held against rotation with the shaft 66 through the medium of the dog 71 engaging the teeth of the ratchet, as seen in Fig. 4, and the pawl 69 engaging the teeth 70.

With the parts constructed and arranged substantially as hereinbefore described and with such parts in the position in which they are shown in Fig. 1, ready for playing, the operation is as follows:

Normally, when there is no music sheet in the instrument, the edge guides 44 are pressed inward to their greatest extent so that the distance between them is less than the width of the narrowest sheet. When the sheet is introduced, the outturned terminals 46 of these edge guides permit of its ready insertion and the pressure of the edges of the sheet upon the inner faces of these edge guides overcomes the pressure of the springs 47, so that the edge guides are moved outward or away from each other to accommodate the sheet no matter what width it may be. If the sheet when thus introduced is not central, the pressure of one edge of the note sheet against its edge guide will be greater than that of the other edge which causes the carriage 33 and the parts movable therewith to move in the direction of the greater pressure and this

causes the friction wheel 29 to be brought into contact with the corresponding disk 53 or 54 which, in turn, causes the toothed wheel 26 to revolve in one direction or the other and by reason of its engagement with the toothed segment 24 moves the latter on its pivot, and such movement through the connection 22 and 23 with the transmission mechanism—10, 11, etc.—which moves the music spool in the proper direction to centralize the sheet. From thence on during the playing, the least deviation of the note sheet to the right or left will throw the friction wheel 29 out of contact with the one disk and into contact with the other, 80 or vice versa and thus through the medium of the toothed segment and the connections above described keep the sheet centralized throughout the playing of the piece.

Upon the rewind the friction wheel 29, 85 the disks 53, 54, the toothed segment, etc., are idle and perform no function.

Modifications in detail may be resorted to without departing from the spirit of the invention or sacrificing any of its advantages.

By "transmission mechanism" or "transmission device," I mean the members 10—11, the back and forth movement of which transmits motion to the music spool 95 4, moving it to the right or left.

What is claimed as new is:—

1. In a device of the character described, mechanical music-spool-moving sheet controlling means embodying friction means 100 out of contact with but under the control of a note sheet.

2. In a device of the character described, a swinging carrier and friction music-spool-moving means movable therewith and out 105 of contact with but under the control of a note sheet for controlling said sheet.

3. In a device of the character described, a swinging carrier, a transmission device and interposed friction music-spool-moving 110 means controlled by said carrier and out of contact with but under the control of a note sheet.

4. In a device of the character described, a swinging carrier, music-spool-moving 115 mechanism embodying friction means controlled by the movements thereof and under the control of a note sheet, a transmission mechanism and intermeshing connections between said transmission mechanism and the 120 friction device.

5. In a device of the character described employing a music spool and note sheet, a swinging carrier, edge guides movably mounted thereon, and music-spool-moving 125 means embodying a friction transmission mechanism actuating device.

6. In a device of the character described employing a music-spool and perforated sheet, a swinging carrier, spring actuated 130

- edge guides movably mounted thereon and a friction control device one member of which is movable with said carrier for moving the music spool laterally.
- 5 7. In a device of the character described employing a music-spool and perforated sheet, a swinging carrier, spring actuated edge guides movably mounted thereon, a friction control device one member of which 10 is movable with said carrier for moving the music spool laterally, and means connecting said edge guides to move them in unison.
- 15 8. In a device of the character described employing a music-spool and perforated sheet, a swinging carrier, spring actuated edge guides movably mounted thereon, a friction control device one member of which 20 is movable with said carrier for moving the music spool laterally, means connecting said edge guides to move them in unison, and means for moving said edge guides out of contact with the edges of a note sheet upon the rewind.
- 25 9. In a device of the character described employing a perforated sheet, a movable carrier, movably mounted edge guides thereon, a friction wheel carried by said carrier, disks between which said friction wheel is movable, and a transmission mechanism controlled by said friction wheel and disks.
- 30 10. In a device of the character described employing a perforated sheet, a swinging carrier, movably mounted edge guides thereon, a friction wheel carried by said carrier, disks between which said friction wheel is 35 movable, and a transmission mechanism controlled by said friction wheel and disks.
- 40 11. In a device of the character described, edge guides controlled by a note sheet, a transmission mechanism, and means for giving lateral movement to the music spool only, said means embodying an interposed friction control.
- 45 12. In a device of the character described, edge guides controlled by a note sheet, a transmission mechanism, an interposed friction control, and intermeshing means for moving the music spool only laterally.
- 50 13. In a device of the character described employing a music-spool and perforated sheet, a transmission mechanism and a friction device controlling the same and out of contact with but mechanically under control of a note sheet for moving the music 55 spool laterally.
- 60 14. In a device of the character described employing a music-spool and perforated sheet, edge guides applicable to note sheets of different widths, a transmission device 65 and interposed friction control mechanism for moving the music spool laterally.
15. In a device of the character described, edge guides applicable to note sheets of different widths, a transmission device and interposed revoluble friction control mecha-
- nism movable independent of the edge guides.
16. In a device of the character described, a wholly mechanical sheet controlling means embodying pivotally mounted edge guides 70 and a revoluble friction control out of contact with the note sheet.
17. In a device of the character described, a wholly mechanical sheet controlling means embodying pivotally mounted edge guides, 75 a friction control and a transmission device governed by said friction control for moving the note sheet laterally.
18. In a device of the character described, a wholly mechanical sheet controlling means 80 embodying pivotally mounted edge guides, a friction control and a transmission device governed by said friction control for moving the note sheet laterally and embodying a pivoted member and means coöperating therewith and under the control of the friction control.
19. In a device of the character described, a wholly mechanical sheet controlling device 85 embodying pivotally mounted edge guides and a friction control and a transmission device governed by said friction control for moving the note sheet laterally and embodying a pivoted toothed segment and a gearing meshing therewith. 95
20. In a device of the character described, a wholly mechanical sheet controlling device embodying pivotally mounted edge guides and a friction control and a transmission device governed by said friction control and 100 embodying a pivoted toothed segment, a gearing meshing therewith and means for throwing said friction control out of operation upon the rewind.
21. In a device of the character described, 105 a wholly mechanical sheet controlling means embodying pivotally mounted edge guides, a revoluble friction control and means for throwing said friction control out of operation upon the rewind. 110
22. In a device of the character described, a wholly mechanical sheet controlling means embodying pivotally mounted edge guides, a friction control, a transmission device governed by said friction control, and means for 115 throwing said friction control out of operation upon the rewind.
23. In a device of the character described, a wholly mechanical sheet controlling means embodying pivotally mounted edge guides, 120 a friction control and a transmission device governed by said friction control and embodying a pivoted member, means coöperating therewith and under the control of the friction control, and means for throwing 125 said friction control out of operation upon the rewind.
24. In a device of the character described, an automatically reversible revoluble frictional mechanical sheet controlling mech-

- 5
- nism under the control of a note sheet and a transmission mechanism governed thereby.
25. In a device of the character described, an automatically reversible revolute frictional mechanical sheet controlling mechanism under the control of a note sheet and a transmission mechanism governed thereby and embodying automatically reversible actuating means.
- 10 26. Edge controlling means for constant contact with note sheets of different widths, a transmission mechanism and interposed devices embodying revolute friction means for operating the latter and controlled by said edge controlling means.
- 15 27. Edge controlling means mounted for movement in opposite directions and also in the same direction, and mechanical means governed thereby for centralizing a traveling note sheet.
- 20 28. Edge controlling means adapted for movement in unison transversely to the travel of the note sheet, and mechanical means controlled from said edge guide means for centralizing a note sheet.
- 25 29. A music spool with relatively fixed flanges, a relatively fixed trackerbar, wholly mechanical means for moving a music spool laterally and causing automatic registration between the openings of the trackerbar and the perforations of a note sheet.
- 30 30. A trackerbar, a music spool with relatively fixed flanges, mechanical means for cooperation with note sheets of different widths for moving a music spool laterally and insuring automatic registration of the holes of the trackerbar and the perforations of a note sheet.
- 35 31. A trackerbar, a music spool with relatively fixed flanges, movably mounted edge guides and mechanical controlling means movable therewith for moving a music spool laterally and insuring automatic registration between the openings of the trackerbar and the perforations of a note sheet.
- 40 32. A trackerbar, a music spool with relatively fixed flanges, edge contacting means movable relatively to the trackerbar and mechanical means controlled by said edge contacting means to move a music spool laterally and insure accurate registration between the trackerbar and note sheet.
- 45 33. An endwise movable music spool having relatively fixed flanges, and a wholly mechanical sheet-controlling mechanism embodying edge-contacting means movable to and from the edges of a note sheet to give endwise movement to said music spool.
- 50 34. Movably mounted edge contacting means, a music spool with relatively fixed flanges, means for moving said music spool endwise and a wholly mechanical mechanism interposed therebetween and controlled by a note sheet.
- 55 35. Movably mounted edge contacting means, means for moving a music spool endwise and a wholly mechanical mechanism interposed therebetween and controlled by a note sheet and automatically reversible.
- 60 36. In a device of the character described, 70 mechanical sheet controlling means embodying friction means under the control of a note sheet.
- 65 37. In a device of the character described, 75 a swinging carrier and friction means movable therewith and under the control of a note sheet for controlling said sheet.
- 70 38. In a device of the character described, 80 a swinging carrier, a transmission device and interposed friction means controlled by said carrier and under the control of a note sheet.
- 75 39. In a device of the character described, 85 a transmission mechanism and a friction device controlling the same and mechanically under control of a note sheet.
- 80 40. In a device of the character described, 90 mechanical music-spool-moving sheet controlling means embodying friction means under the control of a note sheet.
- 85 41. In a device of the character described, 95 mechanical sheet controlling means embodying revolute friction means under the control of a note sheet.
- 90 42. In a device of the character described, 100 mechanical sheet controlling means embodying revolute friction means out of contact with but under the control of a note sheet.
- 95 43. A fixed trackerbar, automatic mechanical means for moving a note sheet in directions laterally to its path of movement for insuring automatic registration of the holes of the trackerbar and the perforations of the note sheet.
- 100 44. A fixed trackerbar, automatic rotatable mechanical means for moving a note sheet in directions laterally to its path of movement for insuring automatic registration of the holes of the trackerbar and the perforations of the note sheet.
- 105 45. A fixed trackerbar, automatic mechanical means out of contact with the note sheet for moving a note sheet in directions laterally to its path of movement for insuring automatic registration of the holes of the trackerbar and the perforations of the note sheet.
- 110 46. A wholly mechanical sheet controlling mechanism embodying revolute edge controlled means to give endwise movement to a 115 music spool.
- 115 47. A wholly mechanical sheet controlling means embodying sheet controlled friction mechanism for automatically insuring registration of the holes of a trackerbar and the perforations of a note sheet.
- 120 48. A wholly mechanical sheet controlling means embodying sheet controlled friction mechanism for automatically insuring registration of the holes of a trackerbar and the 125
- 125 49. A wholly mechanical sheet controlling means embodying sheet controlled friction mechanism for automatically insuring registration of the holes of a trackerbar and the 130

perforations of a note sheet, and edge contacting means movable by engagement of the sheet therewith to control said mechanical means.

5. 49. A wholly mechanical sheet controlling means embodying sheet controlled friction mechanism for automatically insuring registration of the holes of a trackerbar and the perforations of a note sheet, and sheet controlled means for governing the operation of said mechanical means.

10. 50. A mechanical mechanism embodying

an oscillatory sector and operated directly from a note sheet for causing the registration between a traveling note sheet and 15 trackerbar.

51. A non-extensible music spool and a mechanical mechanism independent of the trackerbar and operated directly from a note sheet for causing the registration be- 20 tween a traveling note sheet and trackerbar.

In testimony whereof I affix my signature.

GEORGE P. BRAND.
